24-HOUR DIRECT-READING CLOCK

Eric J. Uhlig, Haddon Heights, and John R. Lewis, Collingswood, N. J., assignors to Wickes Engineering and Construction Company, Camden, N. J., a corporation of New Jersey

Application June 6, 1952, Serial No. 292,072

8 Claims. (Cl. 58—125)

1

This invention relates to direct-reading clocks or the like, and more particularly to direct-reading clocks which indicate time on a 24-hour basis.

Drum-type direct-reading clocks operating on a 12-hour cycle are well known in the art. Such clocks normally have an hours drum with the numbers 0 through 12 thereon, a tens of minutes drum with the numbers 0 through 5 thereon, a minutes drum with the numbers 0 through 9 thereon, and a seconds drum with indicia for numbers 00 through 59 thereon. The seconds drum is driven, through appropriate gearing, by a synchronous motor; and the minutes, tens of minutes and hours drums are coupled back to the seconds drum through Geneva-movement mechanisms so that they move intermittently in proper time-indicating fashion.

Ten, or even twelve numbers of adequate size for easy reading can be put around a drum without the drum and clock case becoming excessively large and bulky. A 24-hour clock with the numbers 0 through 24 arranged on a single drum would be so large and cumbersome as to be impractical for most applications.

As an alternative to having a single hours drum with numbers 0 through 24 thereon, separate hours and tens of hours drums may be considered. The problem immediately encountered arises from the fact that the hours drum must contain ten numbers but a 24-hour cycle is not evenly divisible by ten. Therefore, the hours drum must successively indicate the discontinuous series of numbers 0, 1, 2, 3, 4, 5, 6, 7, 8, 9, 0, 1, 2, 3, 4, 5, 6, 7, 8, 9, 0, 1, 2, 3, 4 and then 0 during one 24-hour cycle.

While others have worked on 24-hour direct-reading clocks, so far as we know no one has succeeded in completely satisfying the needs of those in the communications, transportation, military and naval fields who prefer such a time-piece. It is therefore a general object of the present invention to provide a 24-hour direct-reading clock which combines good legibility with compactness in physical size.

It is another object to provide a 24-hour clock employing a mechanism requiring a minimum number of parts.

It is a further object to provide a clock which is reliable, simple in construction and relatively inexpensive to manufacture.

It is a further object to provide a clock wherein the four visible numbers indicating hours and minutes are of equal size and are equally spaced so as to maximize readability.

2

It is a further object to provide a clock wherein the hours and minutes drums may be reset independently without any possibility of the drums getting out of proper time-indicating synchronism.

Other objects and novel features of the construction and arrangement of parts comprising this improved clock will be apparent as the description of the invention progresses.

According to the present invention, separate number drums are used for the tens of hours, hours, tens of minutes, minutes and seconds. The seconds drum is rotated at a constant speed of one revolution per minute by a clock motor. Geneva-movement mechanisms are interposed between the five drums so that all drums except the driven seconds drum are rotated with intermittent motions in time-indicating fashion.

The hours drum, having numbers 0 through 9 thereon, is advanced one number (thirty-six degrees) every hour by a Geneva mechanism driven from the tens of minutes drum. The tens of hours drum has numbers 0, 0, 1, 1 and 2 distributed over 180 degrees of its peripheral surface. A Geneva mechanism driven from the hours drum advances the tens of hours drum one number (thirty-six degrees) every five hours. Therefore, the first number 0 on the tens of hours drum is visible for five hours while numbers 0, 1, 2, 3 and 4 on the hours drum appear in succession. The second number 0 on the tens of hours drums is visible with numbers 5, 6, 7, 8 and 9 on the hours drum. The first number 1 on the tens of hours drum is visible with numbers 0 through 4 of the hours drum, and the second number 1 is visible with numbers 5 through 9. Then the number 2 on the tens of hours drum is visible for four hours with the numbers 0, 1, 2 and 3 on the hours drum. This brings the reading up to 23 hours. At the end of the four hour period during which the 2 on the tens of hours drum is visible, the hours drum shifts to indicate number 4, and the clock then reads time 2400. At this instant, a transfer mechanism goes into operation whereby a detent or latch locks the tens of hours and the hours drums together and both are rapidly rotated 216 degrees, by overdriving means, through the blank portion of the tens of hours drum and the numbers 4, 5, 6, 7, 8 and 9 of the hours drum. The clock then reads time 0000 for some seconds before changing to time 0001. The recycling procedure takes a matter of seconds and can be made to occur when the clock indicates time 2359 if desired, or at any other suitable time.

40

45

50

55

A more detailed description of the invention will now be made with reference to the accompanying drawings wherein:

Figure 1 is a representation of the overall mechanism of one embodiment of the invention, the view being that seen from the line 1—1 of Fig. 2.

Figure 2 is an end elevation.

Figure 3 is a sectional view taken on the line 3—3 of Fig. 1.

Figure 4 is a sectional view taken on the line 4—4 of Fig. 1.

Figure 5 is a sectional view taken on the line 5—5 of Fig. 1.

Figure 6 is a sectional view taken on the line 6—6 of Fig. 1.

Figure 7 is a sectional view taken on the line 7—7 of Fig. 1.

Figure 8 is a sectional view taken on the line 8—8 of Fig. 7.

Figure 9 is a graphical representation of the motions of parts of the mechanism which will be used in explaining the operation thereof.

Figure 10 is a representation of the distribution of numbers around the various drums.

Figure 11 is a front elevation showing the appearance of a 24-hour direct-reading clock.

Referring now in greater detail to the drawings, wherein like parts in the several views are given the same numeral, a frame 14 has journaled therein a compound shaft consisting of a main shaft 15 and a concentric sleeve shaft 16, both shafts being freely rotatable relative to the frame and to each other. An auxiliary shaft 17 is also journaled in frame 14 in parallel spaced relationship with the compound shaft. A clock motor or synchronous gear motor 18 mounted on frame 14 has an output shaft 19 provided with a pinion 20 for driving a seconds assembly.

The seconds assembly as a unit is freely rotatable on main shaft 15 and it comprises a gear wheel 21 meshed with pinion 20, a seconds drum 22 with indicia thereon as represented in Fig. 10, and a Geneva driver 23 having a drive pin 24 and a locking shoulder 25. Motor 18 drives the seconds assembly at the constant speed of one revolution per minute. Gear wheel 21 drives gear 26 which is fixed on auxiliary shaft 17 so that shaft 17 also rotates at one revolution per minute for purposes which will become apparent as the description proceeds.

The Geneva driver 23 drives a Geneva star wheel 29 which is freely rotatable on shaft 17 and which has six drive slots 30 and six lock surfaces 31, the construction being shown to advantage in Fig. 3. Geneva star wheel 29 is coupled to gear wheel 32 through a spring-loaded ratchet 33, the teeth of the ratchet being arranged so that star wheel 29 drives gear wheel 32, but the latter can be overdriven. Both are freely rotatable on shaft 17. Once in every complete rotation of the seconds assembly, pin 24 drives star wheel 29 and gear wheel 32 sixty degrees. This motion is imparted to gear wheel 35 to cause a thirty-six degree rotation of the latter, the reduction being due to the gear ratio.

It will be understood that Geneva mechanisms are old in the art and that the present invention is not on Geneva mechanisms per se. Therefore, it will not be necessary to describe herein the Geneva mechanism in great detail.

Gear wheel 32 intermittently drives a minutes assembly including gear wheel 35, minutes drum 36 with indicia thereon as shown in Fig. 10, and a Geneva driver 37 including drive pin 38. The

minutes assembly is fixed on shaft 15 as is the minutes set wheel 40. When set wheel 40 is used to set the minutes drum 36 to the proper time, the motion is not transmitted back to the seconds assembly by reason of the overriding action of ratchet 33.

Once during every revolution of minutes drum 36 and Geneva driver 37, drive pin 38 causes a thirty-six degree rotation of Geneva star wheel 10 42. Star wheel 42, as shown to advantage in Fig. 4, consists of a driven wheel 43 with ten notches and a lock wheel 44 having ten lock surfaces. The two-part construction with each part operative in a separate plane is employed because 15 of the relatively large number of teeth needed. Star wheel 42 is directly coupled by shank 45 to gear wheel 46; all as a unit are freely rotatable on shaft 17. Each thirty-six degree rotation of gear wheel 46 causes a sixty degree rotation of 20 gear wheel 47 by reason of the gear ratio.

Gear wheel 46 causes rotation of a tens of minutes assembly which, as a unit, is freely rotatable on main shaft 15 and which consists of a gear wheel 47, a tens of minutes drum 48 with indicia 25 thereon as represented in Fig. 10, and a Geneva driver 49, with drive pin 50. Driver 49 drives Geneva star wheel 53, shown to advantage in Fig. 5. Star wheel 53 has six notches 54 and it is coupled to gear wheel 55 through spring-loaded ratchet 56. Once during each rotation of the 30 tens of minutes drum 48 and driver 49, star wheel 53 and gear wheel 55 are made to rotate sixty degrees, which in turn causes a thirty-six degree rotation of gear wheel 58.

35 An hours assembly is fixed on sleeve shaft 16 and it consists of gear wheel 58, hours drum 59 having indicia thereon as represented in Fig. 10, and a Geneva driver 60 having two driver pins 61 and 62 disposed 180 degrees apart. An hours 40 set wheel 63 is also fixed on sleeve shaft 16 for setting the hours drum to the correct time. During the setting procedure, ratchet 56 is overridden so that the motion is not transmitted back to the tens of minutes drum 48.

45 A compound Geneva star wheel 64 and directly coupled gear wheel 65 are freely rotatable as a unit on auxiliary shaft 17 and are rotated thirty-six degrees once during every half revolution of hours drum 59 and driver 60. Star 50 wheel 64 is shown to advantage in Fig. 6; it consists of a slotted driven disk 67 and a lock disk 68 having six concave lock surfaces. It will be noted that a portion 69 of the periphery of lock disk 68 is without lock surfaces, for reasons which 55 will be treated as the description proceeds.

A tens of hours assembly consisting of a tens of hours drum 70 with tens of hours numbers 0, 0, 1, 1 and 2 thereon, a gear wheel 71, and a mutilated Geneva star wheel 72 is freely rotatable as a unit on sleeve shaft 16. Gear wheel 71 is meshed with gear wheel 65 on auxiliary shaft 17. Therefore, gear wheel 71, tens of hours drum 70, and mutilated Geneva wheel 72 are driven thirty-six degrees every time the Geneva 60 mechanism 60, 64 operates.

A circular notched cam 75 is fixed on sleeve shaft 16 so that it is maintained in a predetermined relationship with the hours drum 59, which is also fixed on sleeve shaft 16. A stationary 70 sector cam 76 having an internal concave cam surface is mounted on frame 14 by means of supports 77, 77. A Geneva driver 80 is fixed on auxiliary shaft 17 and is provided with six driver pins spaced thirty degrees apart. Five of the 75 driver pins 81 are of a length to be operative

solely in the plane of mutilated star wheel 72, while a sixth drive pin 82 is elongated to be operative in a plane between mutilated star wheel 72 and cam 75. Geneva driver 80 is rotated at the constant speed of one revolution per minute by shaft 17 which is in turn driven by motor 18 through pinion 20, and gear wheels 21 and 26.

As shown to advantage in Figs. 7 and 8, mutilated star wheel 72 has five teeth 84 which are driven by the five driver pins 81. There is a sixth tooth 85 reciprocably mounted on mutilated wheel 72. The limits and direction of reciprocation are determined by slots 86 and 87 in the reciprocable tooth 85 and pin 88 extending from mutilated wheel 72, and sleeve shaft 16. A cam follower pin 90 extends from one end of reciprocable tooth 85 and rides on the surface of cam 75. A spring 91 mounted at 92 on mutilated star wheel 72 urges cam follower pin 90 against the surface of cam 75. In the drawings, the reciprocable tooth 85 is shown in one of its extreme positions wherein cam follower pin 90 is in the notch on cam 75. In this position, the reciprocable tooth 85 extends out radially like fixed teeth 84 on mutilated star wheel 72, and is in a position to be operated upon by elongated driver pin 82 of Geneva driver 80.

The reciprocable tooth 85 is provided with a foot 94 which extends into the plane of fixed cam 76. Fixed cam 76, when engaged by foot 94, prevents cam follower pin 90 from falling into the notch on cam 75 when the clock mechanism is in a position to indicate time 1200. Fixed cam 76 also serves in effecting a lifting of cam follower pin 90 out of the notch on cam 75 to unlock drums 59 and 70 following the recycling operation occurring at time 2400.

Fig. 10 illustrates the number indicia arranged around 360 degrees of the peripheral surfaces of the various drums. It will be noted that the second drum 22 has numbers for sixty seconds counting by fives, the minutes drum 36 has numbers 0 through 9, the tens of minutes drum 48 has numbers 0 through 5, the hours drum 59 has numbers 0 through 9, and the tens of hours drum 70 has numbers 0, 0, 1, 1 and 2. The seconds drum 22 may have the numbers on a color-coded background with a separate color for each quarter minute. The numbers are evenly distributed around all drums except the tens of hours drum 70, which has the numbers distributed around half of the peripheral surface. In Fig. 10, the numbers are arranged to move upwardly past a window, whereas in the other figures of the drawings the number drums move downwardly past the window. Either arrangement of the numbers may be used.

Fig. 11 illustrates the appearance of the clock when provided with a mask 96 having windows through which the numbers on the disks are visible.

The operation of the 24-hour direct-reading clock will now be described and the chart of Fig. 9 will be used to explain the operation of the transfer means associated with the hours drum 59 and the tens of hours drum 70. Motor 18 drives the seconds drum 22 at the constant speed of one revolution per minute. Once during every revolution of seconds drum 22, minutes drum 36 is advanced thirty-six degrees or one-tenth of a revolution, the motion being transmitted from Geneva driver 23 through Geneva star wheel 29, ratchet coupling 33 and gear wheels 32, 35. Once during every revolution of minutes drum 36 the tens of minutes drum 48 is advanced

sixty degrees or one-sixth of a revolution, the motion being transmitted from Geneva driver 37 through Geneva star wheel 42, shank 45 and gears 46, 47. Once during each revolution of the tens of minutes drum 48, the hours drum 59 is advanced thirty-six degrees or one-tenth of a revolution, the motion being transmitted from Geneva driver 49 through Geneva star wheel 53, ratchet coupling 56 and gears 55, 58. Once during each half revolution of hours drum 59, the tens of hours drum 70 is rotated thirty-six degrees or one-tenth of a revolution, the motion being transmitted from Geneva driver 60 through Geneva star wheel 64 and gears 65, 71. Drums 36, 48, 59 and 70 are normally stationary and are advanced quickly by the Geneva mechanisms from a position where one number on the drum is visible to a position where the next higher number is visible.

Drums 36, 48, 59 and 70 are thus advanced in time-indicating fashion from time 0001 to time 2400. It will be noted that the tens of hours drum 70 is advanced every five hours from number 0, to number 0, to number 1, to number 1 and to number 2. The motion of the tens of hours drum 70 is illustrated by dotted line 97 in Fig. 9, the vertical portions indicating the periods of time when the drum is stationary and the horizontal portions indicating the times at which the drum is rotated to reveal the next number. The repeated numbers 0 and 1 are distinguished in Fig. 9 by subscripts 1 and 2. The horizontal axis of Fig. 9 indicates angular relationship relative to a fixed point on frame 14.

The motion of the hours drum 59 is represented in Fig. 9 by the line 98, the vertical portions representing the hourly periods during which the drum is stationary and the horizontal portions indicating the thirty-six degree rotational shifts made by the drum once per hour.

Reciprocable tooth 85 rotates with tens of hours drum 70 so the line 97 in Fig. 9 also represents the motion of the reciprocable tooth 85. Similarly, notched cam 75 rotates with the hours drum 59, and its motion is represented by line 99 in Fig. 9. Wherever lines 97 and 98 intersect, the cam-following pin 90 of reciprocable tooth 85 is in a position to be urged by spring 91 into the notch on cam 75. It will be noted from Fig. 9 that there is a period of one hour between time 1200 and time 1300 during which lines 97 and 98 intersect, indicating that pin 90 is in line with the notch in cam 75. However, reciprocable tooth 85 is prevented from shifting by reason of its foot 94 encountering the stationary cam 76. The arrow 99 in Fig. 9 indicates the sector over which the stationary cam 76 is operative in this manner. Lines 97 and 98 again intersect at the point designated 100 on Fig. 9. This occurs at time 2400 and the elements of the latching or transfer means are then in the positions shown in Figs. 1, 7 and 8. As shown to advantage in Fig. 7, cam-following pin 90 has fallen into the notch on cam 75 allowing reciprocable tooth 85 to extend radially into a position where it may be operated upon by elongated pin 82 of Geneva driver 80. Driver 80, being fixed on auxiliary shaft 17 is always driven at the constant uniform speed of one revolution per minute. When the pin 90 of reciprocable tooth 85 is in the notch of cam 75, the tens of hours drum 70 and the hours drum 59 are locked together, since tooth 85 is connected to tens of hours drum 70 and cam 75 is connected to hours drum 59. Geneva driver 80 then rapidly drives mutilated star wheel 72, and drums 70 and 59,

through 216 degrees to a position where numbers 0 on both drums are in reading position. Drums 70 and 59 are overdriven relative to the tens of minutes drum, the overdriving being possible because of the presence of ratchet coupling 58 between drums 59 and 43. When drums 70 and 59 are locked and rotated, there is no interference between Geneva driver 60 and Geneva star wheel 64; this is because a portion 69 of the lock disk 63 is cut away. Pins 81 of Geneva driver 60 never engage teeth 84 of mutilated star wheel 72 except following the engagement of elongated pin 82 with reciprocable tooth 85 because between time 0001 and time 2400 the teeth 84 do not extend into the circle of rotation of pins 81.

As the locked drums 70 and 59 are quickly rotated from positions indicating numbers 24 through -5, -6, -7, -8, -9 to 00, reciprocable tooth 85 rotates with the drum until, at time 00 hours, the foot 84 of tooth 85 engages stationary cam 76 resulting in cam-following pin 93 being lifted out of the notch in cam 75. Stationary cam 76 keeps reciprocable tooth 85 in its withdrawn position until after time 1200 as represented by line 98 in Fig. 9.

In setting the clock to the correct time, the minutes drum 36 fixed on main shaft 15 is rotated by knurled wheel 49 which is also fixed on main shaft 15. The rotation of minutes drum 36 also results in the advancement of the tens of minutes drum 43 through the action of the Geneva mechanism 37, 42 between the drums. No more than six revolutions of the minutes drum are needed to set drums 36 and 43 to any indication between 00 and 59 minutes. The rotation of minutes drum 36 does not react back to the seconds drum 22 because ratchet 33 between the drums is overridden. An accurate setting of the seconds drum 22 is made by switching the electricity to motor 18.

Hours drum 59 fixed on sleeve shaft 16 to set by rotating knurled set wheel 63 which is also fixed on sleeve shaft 16. The rotation of hours drum 59 also results in the advancement of the tens of hours drum 70 through the action of Geneva mechanism 60, 64 between the drums. No more than three revolutions of hours drum 59 are needed to set the two drums to any reading between 00 and 24 hours. The rotation of hours drum 59 is not transmitted back to tens of minutes drum 43 by reason of ratchet 58 being overridden.

Ratchet 33 has ten teeth and minutes drum 36 has ten number positions. Therefore, the re-setting procedure cannot disturb the necessary synchronous relationship between drums 22 and 36. Similarly, ratchet 58 has ten teeth and hours drum 59 has ten number positions so as to maintain synchronism between drums 43 and 59.

It will be understood by those skilled in the art that a construction may be employed wherein the tens of hours drum carries solely the number 0, 1 and 2 and the drum is advanced at ten-hour intervals rather than five-hour intervals.

Other variations and modifications of the parts and of their positions and arrangements may be made by those skilled in the art without departing from the nature of the invention within the scope of what is hereinafter claimed.

What is claimed is:

1. In a 24-hour direct-reading clock or the like, the combination comprising an hours drum having the numbers 0 through 9 thereon, means operative once per hour to advance said drum one number, a tens of hours drum having the num-

bers 0, 1 and 2 thereon, a Geneva mechanism operatively interposed between said drums to advance said tens of hours drum at least once during every complete cycle of the hours drum, and transfer means operative responsively to a predetermined relative position of said hours and tens of hours drums to lock them together and quickly rotate them substantially 216 degrees.

2. A 24-hour direct-reading clock comprising an hours drum and a tens of hours drum, means for driving the hours drum, Geneva movement means operatively connecting the tens of hours drum with the hours drum, a detent operative to lock the hours and tens of hours drums from the time the number 2 of the tens of hours drum and the 4 of the hours drum are both in the viewing position until the numbers zero on both drums are in the viewing position, and overdriving means engaging said detent to effect said movement of the locked hours and tens of hours drums.

3. A 24-hour direct-reading clock or the like, comprising an hours drum with the numbers 0-9 evenly spaced thereabout, a tens of hours drum with the numbers 0, 0, 1, 1 and 2 spaced over 180 degrees of the drum, means for driving the hours drum, Geneva movement means operative after each half revolution of the hours drum to turn the tens of hours drum 36 degrees, a detent operative every 24 hours to lock the hours and tens of hours drums together, and overdriving means operative responsively to said detent to rotate said locked drums substantially 216 degrees.

4. In a 24-hour direct-reading clock or the like, the combination of an hours drum having the numbers 0 through 9 evenly spaced thereabout, means for advancing said drum 36 degrees every hour, and overdriving means operative after every 864 degrees of rotation of said drum to quickly rotate the drum 216 degrees.

5. In a 24-hour direct-reading clock or the like, the combination of an hours drum having the numbers 0 through 9 thereon, a window disposed to reveal one of said numbers at a time for viewing, means operative every hour for advancing said drum to reveal the next successive number, and overdriving means operative every 24 hours to quickly advance said drum through the positions revealing numbers 4 through 9.

6. A 24-hour direct-reading clock comprising individual indicating drums for tens of hours, hours, tens of minutes, minutes, and seconds, a driving motor geared to the seconds drum, Geneva mechanisms coupling the drums so that they rotate in time-indicating fashion, latch means operative every third time the number 4 on the hours drum appears in the viewing position, and overdriving means deriving power from said driving motor operative cooperatively with said latch means to quickly rotate the hours drum to a position where the number zero is visible.

7. A 24-hour direct-reading clock comprising individual indicating drums for tens of hours, hours, tens of minutes, minutes, and seconds, a driving motor geared to said seconds drum, Geneva mechanisms coupling the drums so that they rotate in time-indicating fashion, latch means connected with the hours drum operative every 24 hours, and overdriving means deriving power from said driving motor operative cooperatively with said latch means to quickly rotate the hours drum substantially 216 degrees.

8. A 24-hour direct-reading clock comprising individual indicating drums for tens of hours, hours, tens of minutes and minutes, numbers 0 through 9 distributed around the periphery of

said hours drum, driving means including Geneva mechanisms for driving said drums in time-indicating fashion, latch means connected with the hours drum operative every third time the number 4 on the hours drum reaches a predetermined position, and overdriving means operative responsive to said latch means to quickly rotate the hours drum until the number zero on the drum reaches said predetermined position.
